GAME

William E. Jackson, Jr., New York, N. Y.

Application November 23, 1932
Serial No. 644,002

5 Claims. (Cl. 273—130)

The invention is specifically applicable to those games played by opposing players, wherein the moves of one player must be screened from the observation of the opponent until the game has been finally decided. Games of this sort have been in use for many years. In some cases the opposing players have seated themselves at a distance apart so that the moves of either player would be screened from the other. A representative example of this type of game is that known as "Salvo". At playing this game, the players select an outline on their respective game boards an assumed location for the ships under their command. Various hypothetical shots are then fired and recorded until the vessels of one player have been hypothetically demolished. While the invention is well applicable to this particular type of game, it will of course be understood that it is generally applicable to all games of the type hereinbefore described, wherein the moves of one player are necessarily screened from observation. My invention comprehends particularly a type of screen which is exceptionally simple in construction and economical to manufacture, and which is, moreover, automatically located by the simple movement of placing the game board in position for use. The invention will be fully understood from the following description read in conjunction with the drawing, 30 in which,

Fig. 1 is a perspective view of one embodiment of my invention in position for use.

Fig. 2 is a perspective view of the construction shown in Fig. 1 in partially folded position, and 35 Fig. 3 is an end view of the construction shown in Fig. 1.

Referring to the drawing, 1 designates a game board adapted to be used by one of the opposing players, and 2 indicates a game board adapted to be employed by the adversary. The boards may, of course, comprise movable pieces which are appropriately secured or which operate in channels; or may alternatively, or in addition carry spaces for suitable inscriptions or similar designations which mark the progress of the game. In the game of "Salvo", by which the invention is illustrated, the spaces 3 and 4 respectively are for the purpose of graphically locating the positions of the opposing ships. The various shots fired by the respective players may be indicated in the spaces 5 and 6 respectively, and the hits scored are recorded in circles such as 7 and 8.

Referring specifically to Fig. 3, the type of game board illustrated comprises a cover 10, and 55 a sheet of material 11 having a dark colored sur-

face treated with a mildly adhesive substance such as paraffin. The sheet 12 is thin and translucent, and may for example be formed of tissue paper. The sheet 13 is of transparent flexible material, such as transparent celluloid, and carries printed thereon the figures and spaces which characterize the game. The sheet 12 will normally be bound to sheet 13 by a marginal tape 14, but the two sheets do not adhere to one another. When the sheets are laid upon one another in the order shown in Fig. 3, the marks and designations incidental to the progress of the game are made by writing on the face of the sheet 13 with a suitable stylus. This causes sheet 12 to adhere to sheet 11 along the inscribed line, there- 60 through sheet 12 along the inscribed line.

When the game has been finished all of the lines are obliterated and the game placed in condition for reuse by any movement which breaks 75 the light adhesion between sheets 11 and 12. This may be effected for example by a relative sidewise movement of the two or by blowing the two apart, or, if desired, by lifting sheet 13 and the marginally attached sheet 12 away from the 80 paraffined surfaced sheet 11. Alternatively, the lines may be obliterated by passing a separator between the sheets 11 and 12. The game board 1 similarly includes cover sheet 16, sheet 17 having a dark colored surface treated with a mildly ad- 85hesive substance such as paraffin, the thin translucent sheet 18 which may for example be formed of tissue paper, and the transparent sheet 19 which may for example be formed of celluloid. The sheets 18 and 19 are marginally bound together by the tape 19'. The game boards 1 and 2 are connected along the contiguous edges 20 and 21 by the flap 23. In the type shown, this is merely a tape of cloth, or similar material, glued to the cover portions. A more complicated 95 type of hinge, such as metal leaves articulately connected by a common pintle, may of course be substituted for the relatively simple type shown in the illustration. All such devices which permit the movement of the respective game boards 100 through a dihedral angle may be hereinafter generically referred to as "hinges".

The screening device, per se, comprises the opaque sheet 30 which is secured to the game board 1 by the hinge 31. This hinge may of 105 course be formed of metal, or alternatively of a flap of cloth, and in the construction shown is simply constituted by the cloth tape 32, one edge of which is cemented to the board 1. As a consequence of this construction the sheet 30 is 110

adapted to move through a dihedral angle with respect to the board 1, and the vertex (36) of this dihedral angle is parallel to the vertex of the dihedral angle through which the two game boards move with respect to each other. The two vertices are a small distance apart. The screen also comprises the opaque sheet 40 which is hingedly connected to the board 2 by the flap of cloth tape 41, one edge of which is cemented 10 to the game board 2. A more complicated type of hinge may of course be substituted, but is not preferred. The sheet 40 may be moved through a dihedral angle with respect to the game board 2. The vertex of this dihedral angle is similarly 15 parallel to the vertex of the dihedral angle between the two game boards, and is preferably as far removed therefrom as the vertex 36. The opaque sheets 30 and 40 are connected adjacent the upper margins by the tape 45 which likewise 20 constitutes a hinge, permitting the sheets 30 and 40 to move through a limited dihedral angle with respect to each other, the vertex of which is along the line 46 and is parallel to the vertex of the dihedral angles hereinbefore mentioned.

25 It will be apparent from this description and from the figures that when the game boards 1 and 2 are folded up to be placed away, the screen simultaneously folds and lays inside of the game boards. Whenever it is desired to use the game, 30 the game boards are unfolded or laid out to the horizontal position shown in Fig. 1, and the screen automatically comes into position for use.

The foregoing description is for purposes of illustration and not of limitation, and it is therefore my intention that the invention be limited only by the appended claims or their equivalents, wherein I have endeavored to claim broadly all inherent novelty.

I claim:

- 40 1. Game boards designed for use by opposing players wherein the moves of one player must be invisible to the opponent, comprising a first game board, a second game board, a hinge connecting said first and second game boards and permitting relative movement of the same through a dihedral angle, a first sheet of opaque material, a hinge connecting said first sheet and said first game board, the axis of said hinge being parallel to the vertex of said dihedral angle, 45 a second sheet of opaque material, a hinge connecting said second sheet and said second game board, the axis of said hinge being parallel to the vertex of said dihedral angle, and a hinge connecting said first and second opaque sheets, the axis of said hinge being parallel to the vertex of said dihedral angle, 50 whereby said first and second sheets form a screen between said game boards when the latter are opened and laid on a horizontal surface.
- 55 2. Game boards designed for use by opposing players involving written designations, wherein the designations of one player must be invisible to the opponent, comprising a first game board adapted to receive written designations, a second game board adapted to receive written designations, a hinge connecting said first and second game boards, permitting relative movement of the same through a dihedral angle, a first sheet of opaque material, 60 a hinge connecting said first sheet and said first game board, the axis of said hinge being parallel to the vertex of said dihedral angle, 65 a flap connecting said first sheet and said first game board, the axis of said flap being parallel to the vertex of said dihedral angle, a second sheet of opaque material, 70 a flap connecting said second sheet and said second game board, the axis of said flap being parallel to the vertex of said dihedral angle, and a flap connecting said first and second opaque sheets, the axis of said flap being parallel to the vertex of said dihedral angle, whereby said first and second sheets form a screen between said game boards when the latter are opened and laid on a horizontal surface.

angle, a second sheet of opaque material, a hinge connecting said second sheet and said second game board, the axis of said hinge being parallel to the vertex of said dihedral angle, and a hinge connecting said first and second opaque sheets, the axis of said hinge being parallel to the vertex of said dihedral angle, whereby said first and second sheets form a screen between said game boards when the latter are opened and laid on a horizontal surface.

3. Game boards designed for use by opposing players wherein the moves of one player must be invisible to the opponent, comprising a first game board, a second game board, a hinge connecting said first and second game boards and permitting relative movement of the same through a dihedral angle, a first sheet of opaque material, a hinge connecting said first sheet and said first game board, the axis of said hinge being parallel to the vertex of said dihedral angle, 90 a second sheet of opaque material, a hinge connecting said second sheet and said second game board, the axis of said hinge being parallel to the vertex of said dihedral angle, and a hinge connecting said first and second opaque sheets, the axis of 95 said hinge being parallel to the vertex of said dihedral angle, said first and second sheets being proportioned to lie wholly within said game boards when the latter are folded together.

4. Game boards designed for use by opposing players wherein the moves of one player must be invisible to the opponent, comprising a first game board adapted to receive written designations, a second game board adapted to receive written designations, a hinge connecting said first and second game boards and permitting relative movement of the same through a dihedral angle, a first sheet of opaque material, a hinge connecting said first sheet and said first game board, the axis of said hinge being parallel to the vertex of 105 said dihedral angle, a second sheet of opaque material, a hinge connecting said second sheet and said second game board, the axis of said hinge being parallel to the vertex of said dihedral angle, and a hinge connecting said first and second opaque sheets, the axis of 110 said hinge being parallel to the vertex of said dihedral angle, said first and second sheets being proportioned to lie wholly within said game boards when the latter are folded together.

5. Game boards designed for use by opposing players wherein the moves of one player must be invisible to the opponent, comprising a first game board, a second game board, a flap connecting said first and second game boards and permitting relative movement of the same through a dihedral angle, a first sheet of opaque material, 120 a flap connecting said first sheet and said first game board, the axis of said flap being parallel to the vertex of said dihedral angle, a second sheet of opaque material, 125 a flap connecting said second sheet and said second game board, the axis of said flap being parallel to the vertex of said dihedral angle, and a flap connecting said first and second opaque sheets, the axis of said flap being parallel to the vertex of said dihedral angle, whereby said first and second sheets form a screen between said game boards when the latter are opened and laid on a horizontal surface.
